UNITED STATES PATENT OFFICE.

LAWRENCE E. JOHNSON, OF MELROSE, OTTO T. PETERSON, OF MALDEN, AND LEONARD A. POPP, OF SAUGUS, MASSACHUSETTS, ASSIGNEES TO VICTOR SHOE MACHINERY CO., OF LYNN, MASSACHUSETTS, A CORPORATION OF MASSACHUSETTS.

ROUGH ROUNDER.

Application filed January 6, 1922. Serial No. 527,844.

To all whom it may concern:

Be it known that we, LAWRENCE E. JOHNSON, OTTO T. PETERSON, and LEONARD A. POPP, citizens of the United States of America, and residents of Melrose, in the county of Middlesex, Malden, in the county of Middlesex, and Saugus, in the county of Essex, respectively, all of the State of Massachusetts, have invented certain new and useful Improvements in Rough Rounders, of which the following is a specification.

This invention relates to sole rough rounders and channeling machines to be used in the manufacture of boots and shoes and is an improvement on the machine shown and described in the Patent No. 1,149,369, issued August 10, 1915, to Lawrence E. Johnson.

One object of the present invention is to provide a machine which can be used equally as well on new shoes in the process of manufacture, or upon old shoes being repaired.

Another object of the invention is the provision of means whereby the cutting chisel holds the work in position while the channeling knife is operating.

A further object is the provision of novel means for feeding the work.

A further object is the provision of means whereby the channeling tool may follow the inclination of the sole while the latter is being operated upon.

Another object is the provision of means whereby the channeling tool may be moved out of commission when it is desired to trim the sole without forming a channel therein.

A further object of the invention is the production of a novel means of adjusting the edge gage.

A further object is the provision of two edge gages, one for the welt and the other for the upper; and either of which may be used according to the class of work being performed.

Another object of the invention is the provision of means whereby the channeling knife may be adjusted relatively to the edge gage so that the channel may be cut into the sole at varying distances from the sole edge.

Another object is the provision of means whereby the channel knife may operate when the rough rounding chisel is not in operation.

The invention consists of certain novel features of construction and arrangement

of parts which will be understood readily by reference to the description of the drawings and to the claims to be hereinafter given.

For the purpose of illustrating the invention, one preferred form thereof is shown in the drawings, this form having been found to give satisfactory and reliable results, although it is to be understood that the various instrumentalities of which the invention consists can be variously arranged and organized, and that the invention is not limited to the precise arrangement and organization of the instrumentalities as herein shown and described, except as required by the scope of the appended claims.

Of the drawings:

Figure 1 represents a front elevation of a machine embodying the principles of the present invention,

Figure 2 represents a side elevation of the same,

Figure 3 represents a plan of said machine,

Figure 4 represents a detail in elevation of a portion of the machine to be herein-after referred to,

Figure 5 represents a rear elevation of the work support,

Figure 6 represents a horizontal section of same on line 6, 6 on Figure 5, and

Figure 7 represents a rear elevation of a feeding member adapted to be substituted for the channeling knife when the machine is being used for cutting a channel in a sole already shaped, said view being drawn to an enlarged scale.

Similar characters indicate like parts throughout the several figures of the drawings.

In the drawings, 10 is the base of a frame 11, having bearings 12, in which is revolvably mounted a shaft 13 adapted to be driven by a pulley 14 loosely mounted thereon.

The shaft 13 has secured thereto the cam disk 15 and the eccentrics 16 and 17. This shaft 13 has also secured thereto a fly wheel 18.

The pulley 14 is provided with a hub 19, having a flange 20 thereon, with which contacts the pins 21 secured in the forked end of a lever 22 mounted upon a fulcrum pin 23, said lever 22 having an arm 24 extending therefrom, the outer end of which is con-

nected by means of a rod 25 to a suitable treadle mechanism, which may be of any well known construction and consequently is not shown in the drawings.

5 When the treadle mechanism is operated to depress the arm 24, the lever 22 will cause the pulley 14 to be moved into a frictional engagement with the fly wheel 18, in this manner effecting the rotation of the shaft 13. As soon as the pressure is released from the treadle mechanism, the pulley 14 will move outwardly on the shaft 13 and disengage itself from the fly wheel 18.

15 The fulcrum pin 23 is mounted on the outer end of a bracket 26 secured to a column 27, to the upper end of which the base 10 is secured.

20 The frame 11 has extending therefrom a pin 28 on which is mounted the lever 29, the lower end of which is provided with a roll 30, bearing against the cam 15. This lever 30 is provided with a downward extension 31 between which and the pin 32 on the base 10 is a spring 33 which retains the roll 30 in contact with the periphery of the cam 15 at all times.

25 The upper end of the lever 29 is provided with a bearing 34 in which is mounted a shank 35, the upper end of which is forked as shown at 36 in Figure 1 of the drawings. Between the forked end 36 and the upper end of the bearing 34 is a spring 37, which forces the forked end 36 upwardly. Pivot-
30 ed to the lever 29 at 38 is a lever 39 having formed therein a slot 40, into which extends a pin 41 secured to and extending outwardly from the shank 35. By means of this lever 39, the shank 35 and the forked upper end 36 thereof may be moved downwardly in the bearing 34 against the tension of the spring 37. This movement is performed when it is desired to insert new work to be operated upon, and as soon as the new work is properly positioned, the pressure upon the lever 39 is released and the spring 37 moves the work upwardly against the member 42.

35 This member 42 is slidably mounted upon the plate 43, secured to or formed integral with the upper end of the frame 11, said plate 43 extending into a groove in the under face of the member 42 and forming a guide therefor. This slidable member is provided on one side with a slot 44, in which is positioned a lever 45 pivoted to the frame 11 at 46 and having at its upper end an operating handle 47.

40 The walls of the slot 44 are curved and bear against the edges of the lever 45 so that when the operator actuates the handle 47, the member 42 may be adjusted lengthwise of the plate 43, and secured in an adjusted position by means of the clamping bolt 50 extending through a slot 51 in the slidable member 42.

45 The front end of the slidable member 42

has an opening 52 extending therethrough, in which is positioned the operating end of the presser foot or work-feeding member 54.

50 The rear end of the presser foot 54 ex- 70 tends through a transverse slot in the upper end of a rod 55 and is clamped in position therein by means of a nut 56. By releasing this nut 56 from contact with the work-feeding member 54, the said presser foot 54 may be moved endwise in the slot and again clamped to the member 55 in its adjusted position relatively thereto.

55 The rod 55 extends through a bearing in a member 57 adapted to oscillate about a fulcrum pin 58 secured to the frame 11, and projecting through a downwardly extending flange 57* on said member 57.

60 The lower end of the rod 55 is secured in a housing 59 having a cylindrical opening 85 therethrough, fitted to the eccentric 17.

65 When the shaft 13 is rotated, the rotation of the eccentric 17 will cause the rod 55 to be raised and lowered, and also tilted about the axis of the fulcrum pin 58. As a consequence of this movement, the operating end of the work-feeding member, or presser foot, 54, will be brought into contact with the work and impinge thereon, and then move the work a slight distance before said operating end of said presser foot 54 is again raised from contact with said work to return to its normal position.

70 The front end of the plate 43 has secured thereto a welt gage 60, by means of a screw 61. Beneath the gage 60 is the chisel 62.

75 The chisel 62 is secured by means of a screw 63, or some other device, to a vertical rod 64 mounted in a bearing 65 in the frame 11, and having its lower end clamped to a split member 66 by means of the screw 67.

80 This member 66 extends through a bearing 68 in a member 69, the lower end of which is provided with a cylindrical opening 95 therethrough to receive the eccentric 16.

85 As the shaft 13 rotates, the revolution of the eccentric 16 will cause the chisel supporting member 64 to be reciprocated in its bearing 65. When in the extreme of its upper movement, the edge of the chisel 62 is embedded slightly in the lower face of the welt gage 60, which is made of bronze or some similar soft material so as not to injure the cutting edge of said chisel.

90 The front end of the welt gage 60 extends beyond the sides of the plate 43 and is rounded off as indicated at 70 to permit the shoe to be moved horizontally at various angles while in contact therewith.

95 While the channel is being cut, the cutting edge of the chisel 62 is embedded in the welt gage 60 and prevents the work from being moved during the cutting operation of the channelling tool.

100 The forked end 36 has mounted therein a

block 71 supported upon the alined pins 72, thus providing a means whereby said block 71 may be tilted to accommodate itself to various inclinations of the work during 5 the channelling operation. The tilting of the block 71 is limited in one direction by the block coming into contact with the upper face of the forked portion 36, while the movement in the opposite direction is limited by means of a downwardly extending pin 73 coming into contact with the rear face of said forked portion 36.

The rear end of the block 71 has a vertical groove formed therein, in which is mounted 15 the body portion of the channelling knife 74, the operating end of which extends toward the front of the block with its edge substantially parallel to the upper face of said block.

20 One edge of the body portion of the channelling knife 74 is bevelled and coacts with a bevelled part of an adjustable pin 75, extending from the rear of the block 71 beyond the front face thereof, and having a 25 clamping nut 76 threaded to the projecting end thereof. By turning the nut 76 the channelling knife 74 may be clamped in any desired position. By loosening the nut, the channelling knife may be adjusted to give 30 varying degrees of cut during the formation of the channel.

The upper end of the block 71 is cut away below the operating end of the channelling knife 74 so that when it is desired to use the 35 machine for rough rounding without forming a channel, the channelling knife may be moved down below the upper face of the block so that no cutting operation will be performed. This cut away portion beneath 40 the operating part of the channelling knife also provides a means for taking care of the chips formed during the cutting of the channel.

The shank 36 has a longitudinal groove 77 cut therein, into which extends the reduced end of a threaded member 78, mounted in the bearing 34 for said shank. This construction provides a means for preventing the rotation of the shank 36 within its bearing 34.

50 In the frame 11 is mounted a shaft 78 having an operating handle 79 secured to one end thereof. The opposite end of this shaft 78 has a projecting lug 80 radiating therefrom. This lug 80 extends into an annular groove 81 in the rear end of the pin 28, on which the lever 29 is mounted.

By actuating the handle 79 this pin 28 and 55 all of the parts supported thereon may be moved lengthwise of the axis of said pin 28 into any desired position. This construction provides a means whereby the position of the operating end of the channelling knife may be adjusted longitudinally relatively to the welt gage 60 and the chisel 62.

The eccentrics 16 and 17 are so timed that in the operation of the machine the presser foot 54 and chisel 62 are both at their highest point at the same time, and the cam 15 is so constructed as to permit the cutting operation by the knife 74 to take place at the same time that the chisel 62 and the presser foot 54 are in their highest positions. As a consequence of this condition, the chisel 62 will be in the work when the knife 74 is cutting the work to form a channel therein. Therefore, the chisel 62 will hold the work from lateral movement during the channel cutting operation.

80 The various elements are shown in this position in the drawings with the cutting knife 74 about midway of its stroke.

The shaft 13 rotates in the direction of the arrow *a* on Figure 1 of the drawings, and as the eccentrics 16 and 17 rotate therewith, the presser foot 54 and chisel 62 will immediately commence to move downwardly as these eccentrics 16 and 17 rotate from the positions indicated in the drawings, while the knife 74 will first complete the other half of 85 its cutting stroke and then remain stationary until the point 83 of the cam 15 reaches the roller 30, and at this time the knife 74 will be moved to the left of Fig. 1, preparatory to a new cutting stroke which commences when 90 the point 84 on the cam 15 reaches the roller 30.

95 The eccentric 16 has a greater throw than the eccentric 17, owing to the thickness of the work, and as a consequence, the presser foot 54 will come into contact with the work preparatory to feeding just before the chisel 62 has left the work, and this work will then be fed a predetermined distance before the chisel 62 on its return stroke again enters the work.

100 The presser foot 54, having completed this feeding operation, will again be lifted from the work. The chisel 62 will be forced through a new part of the work and the channelling knife 74 will cut a new part of the channel in the sole.

105 It will be seen that by the construction herein shown and described, the stroke of the knife 74 is divided on opposite sides of a center line perpendicular to the face of the sole being cut, thereby producing a clean-cut channel. This obviously is a great advantage.

110 On the return stroke of the cutting knife 74, the presser foot 54 is in contact with the work which is gripped between said presser foot 54 and the knife 74 and in this manner the work is positively fed a predetermined distance preparatory to another cutting stroke of said knife 74.

115 By constructing the machine as herein shown and described, it is possible to cut the channel in the work even when the chisel 62 is not in the work, as for instance,

when the channel is to be cut close to the edge of the sole and consequently the edge of said sole will not extend outwardly a sufficient distance to be acted upon by said chisel.

This makes a very simple construction of machine for rough rounding soles and cutting the channels therein, which may be used for rough rounding alone or for rough 10 rounding and channeling. The machine is also adapted to rough round soles of new shoes during the process of construction, or old shoes during the process of repairing.

When completed shoes are being operated 15 upon, the end of the member 42 may be used as a gage while bearing against the upper. When the machine is being used as a rough rounder without cutting a channel in the sole, the knife 74 is preferably removed and the feeding member 74^x inserted in its place. The upper face of the member 74^x is preferably provided with a plurality of serrations 85 as indicated in Fig. 7. With this member 74^x in use the presser foot 54 will force the 20 work into contact with the serrations 85 and feed the work a predetermined distance on the return stroke of the work support 36 preparatory to another cutting operation of the chisel 62.

30 The fulcrum pin 28 is provided with a flange 86 which is adapted to contact with the end of the bearing 87 for the pin 28 in the frame 11, thereby limiting the movement of said pin 28 in one direction while movement thereof in the opposite direction is limited by the projecting lug 80 coming into contact with the opposite face of said bearing 87.

When the fulcrum pin 28 has been adjusted to any desired position it may be secured in such position by means of the clamp nut 88.

It will be noted that the cam 15 is so constructed as to provide a quick cutting 45 stroke to the knife 74 and a very slow return to normal position.

It is believed that the operation and many advantages of the invention will be readily understood without further description.

50 Having thus described our invention, we claim:

1. In a machine of the class described, the combination of a work support; a channeling knife mounted therein; a reciprocating chisel; a welt gage with which said chisel coacts; and a substantially vertical rocker member in the upper end of which said support is mounted and means coacting with the lower end of said rocker member for moving 55 said support and knife to cut a channel in the work while the chisel is in the work.

60 2. In a machine of the class described, the combination of a work support; a channeling knife mounted therein; a reciprocating chisel; a welt gage with the under face of

which said chisel coacts; a rocker member for moving said support and knife to cut a channel in the work while the chisel is in the work; and means for removing the chisel from the work prior to the return stroke of 70 the channeling knife.

3. In a machine of the class described, the combination of a work support; a channeling knife mounted therein; a reciprocating chisel; a welt gage with the under face of 75 which said chisel coacts; means for moving said support and knife to cut a channel in the work while the chisel is in the work; means for removing the chisel from the work prior to the return stroke of the channeling knife; and means for forcing said presser foot against said work during the return stroke of the knife thereby feeding the work.

4. In a machine of the class described, the combination of a work support; a channeling knife mounted therein; a reciprocating chisel; a welt gage with the under face of 80 which said chisel coacts; a rocker member in the upper end of which said support is mounted; cam-mechanism coacting with 85 said rocker member for moving said work support and knife in one direction; a spring connected to the lower end of said rocker member for moving said support and knife in the opposite direction; and means for 90 moving the chisel into contact with the edge gage prior to the cutting stroke of the knife and removing it from the work prior to the return stroke of the knife.

5. In a machine of the class described, the combination of a work support; a channeling knife mounted therein; a reciprocating chisel; a welt gage with which said chisel coacts; cam-mechanism for moving said support and knife in one direction; a spring for 100 moving said support and knife in the opposite direction; means for moving the chisel into contact with the edge gage prior to the cutting stroke of the knife and removing it from the work prior to the return stroke of 105 the knife; and means for moving the presser foot into contact with the work prior to the return stroke of said knife.

6. In a machine of the class described, the combination of a work support; a channeling knife mounted therein; a reciprocating chisel; a welt gage with which said chisel coacts; cam-mechanism for moving said work support and knife in one direction; a spring for moving said support and knife in the opposite direction; means for moving the chisel into contact with the edge gage prior to the cutting stroke of the knife and removing it from the work prior to the return stroke of the knife; and an eccentric 110 for moving the presser foot into contact with the work prior to the return stroke of said knife.

7. In a machine of the class described, the combination of a work support; a channel-

ing knife mounted therein; a reciprocating chisel; a welt gage with which said chisel coacts; cam-mechanism for moving said work support and knife in one direction; a 5 spring for moving said support and knife in the opposite direction; an eccentric for moving the chisel into contact with the edge gage prior to the cutting stroke of the knife and removing it from the work prior to the 10 return stroke of the knife; and an eccentric for moving the presser foot into contact with the work prior to the return stroke of said knife.

8. In a machine of the class described, the 15 combination of a work support; a channeling knife mounted therein; a nonrevolute shank to said work support; a rocker member having a bearing at one end to receive said shank; a roller on the opposite end of 20 said member; a revolute cam coacting with said roller; and a spring for retaining said roller in contact with said cam.

9. In a machine of the class described, the 25 combination of a work support; a channeling knife mounted therein; a nonrevolute shank to said work support; a rocker member having a bearing at one end to receive said shank; a spring surrounding said shank between said work support and bearing; a 30 roller on the opposite end of said member; a revolute cam coacting with said roller; and a spring for retaining said roller in contact with said cam.

10. In a machine of the class described, 35 the combination of a work support; a channeling knife mounted therein; a nonrevolute shank to said work support; a rocker member having a bearing at one end to receive said shank; means for moving said work support downwardly; a roller on the 40 opposite end of said member; a revolute cam coacting with said roller; and a spring for retaining said roller in contact with said cam.

45 11. In a machine of the class described, the combination of a work support; a channeling knife mounted therein; a nonrevolute shank to said work support; a rocker member having a bearing at one end to receive said shank; a roller on the opposite end of said member; a revolute cam coacting with said roller; a spring for retaining said roller in contact with said cam; a pin in said shank; a manually-actuated 50 lever pivoted to the rocker lever and provided with a slot to receive said pin.

55 12. In a machine of the class described, a work supporting block having a vertical groove therein; a forked rocker member in which said block is pivotally mounted; a channeling knife having its body portion mounted in said groove and provided with a bevelled edge; an adjustable pin movable endwise in said block having a bevelled face coacting with said bevelled edge; and means 60

for clamping said pin in adjusted position.

13. In a machine of the class described, a work supporting block having a vertical groove therein; a forked rocker member in 70 which said block is pivotally mounted; an L-shaped work-engaging member having its body portion mounted in said groove and provided with a bevelled edge; an adjustable pin movable endwise in said block having 75 a bevelled face coacting with said bevelled edge; and means for clamping said pin in adjusted position.

14. In a machine of the class described, the combination of a work support; a channeling knife mounted therein; means for positively reciprocating said work support in a horizontal direction; an edge gage adapted to coact with the work and having an opening therein; a reciprocating chisel beneath said edge gage having a cutting edge adapted to be moved into contact with said edge gage; and a presser foot above said edge gage with its operating end positioned 85 in said opening.

15. In a machine of the class described, the combination of a work support; a channeling knife mounted therein; means for positively reciprocating said work support in a horizontal direction; an adjustable edge 90 gage adapted to coact with the work and having an opening therein; a reciprocating chisel beneath said edge gage having a cutting edge adapted to be moved into contact with said edge gage; and a presser foot above said edge gage with its operating end positioned 95 in said opening.

16. In a machine of the class described, the combination of a work support; a channeling knife mounted therein; means for positively reciprocating said work support; an edge gage adapted to coact with the work and having an opening therein; a presser foot above said edge gage with its operating end positioned 100 in said opening; a welt gage secured to the under face of said edge gage; and a reciprocating chisel, the cutting edge of which coacts with the under face of said welt gage.

110 17. In a machine of the class described, the combination of a work support; a channeling knife mounted therein; means for reciprocating said work support; an edge gage adapted to coact with the work and having an opening therein; a presser foot above 115 said edge gage with its operating end positioned in said opening; and a welt gage secured to the under face of said edge gage and having a curved edge adapted to engage the edge of the welt; and a reciprocating chisel, the cutting edge of which coacts with the under face of said welt gage.

120 18. In a machine of the class described, the combination of a work support; a channeling knife mounted therein; means for re- 125

- 5 ciprocating said work support; an edge gage having a slot in a side face thereof; a member mounted on a fixed pivot below said edge gage and having an upper portion extending lengthwise of said slot and adapted in its movement about its pivot to adjust said gage relatively to said work support; and a clamping member for said gage extending through a slot therein.
- 10 19. In a machine of the class described, the combination of a work support; a channeling knife mounted therein; means for reciprocating said work support; an edge gage having a slot in a side face thereof and a longitudinal groove in its under face; a fixed guide plate in said groove; a manually actuated pivoted member having a portion thereof extending lengthwise of said slot and adapted in its movement about the pivot of said member to adjust said gage relatively to said work support; and a clamping member for said gage extending through a slot therein.
- 15 20. In a machine of the class described, the combination of a work support; a channeling knife mounted therein; means for reciprocating said work support; a presser foot coacting with said work support; a rod on which said presser foot is mounted; a housing on the lower end of said rod having a cylindrical opening therethrough; a revoluble eccentric fitted to said opening; and a pivoted bearing surrounding said rod at a point intermediate its ends.
- 20 21. In a machine of the class described, the combination of a work support; a channeling knife mounted therein; means for reciprocating said work support; a presser foot coacting with said work support; a rod on which said presser foot is mounted; a housing on the lower end of said rod having a cylindrical opening therethrough; a revoluble eccentric fitted to said opening; a bearing for said rod intermediate its ends and having a flange extending downwardly therefrom; and a fulcrum pin extending through said flange and about the axis of which said bearing is adapted to oscillate.
- 25 22. In a machine of the class described, the combination of a work support; a channeling knife mounted therein; a rocker lever on which said work support is mounted; a horizontal fulcrum pin to which said rocker lever is secured extending from front to rear of said machine; a cam for moving said rocker lever about the axis of said fulcrum pin; and manually actuated means for moving said fulcrum pin endwise.
- 30 23. In a machine of the class described, the combination of a work support; a channeling knife mounted therein; a rocker lever in which said work support is mounted; a horizontal fulcrum pin extending from front to rear of the machine to which pin said rocker lever is secured, said pin being pro-

vided with an annular groove; a cam for moving said rocker lever about the axis of said fulcrum pin; and manually actuated means for coacting with said annular groove for moving said fulcrum pin endwise.

70 24. In a machine of the class described, the combination of a work support; a channeling knife mounted therein; a rocker lever on which said work support is mounted; a horizontal fulcrum pin extending from front to rear of the machine to which pin said rocker lever is secured, said pin being provided with an annular groove; a cam for moving said rocker lever about the axis of said fulcrum pin; a manually actuated oscillating member having a radial projection at one end extending into said annular groove.

75 25. In a machine of the class described, the combination of a work support; a channeling knife mounted therein; a rocker lever on which said work support is mounted; a fulcrum pin to which said rocker lever is secured and provided with an annular groove; a cam for moving said rocker lever about the axis of said fulcrum pin; an oscillating member having a radial projection at one end extending into said annular groove; and an actuating handle secured to the opposite end of said oscillating member.

80 26. In a machine of the class described, the combination of a reciprocating bar; a chisel secured to one end of said bar; a bearing in which said bar is adapted to reciprocate; a revoluble eccentric; a member to one end of which said eccentric is fitted; a slotted member adapted to oscillate in a bearing in the opposite end of said member; and means for clamping said bar to said slotted member.

85 27. In a machine of the class described, the combination of a work support; a channeling knife mounted therein; a reciprocating chisel; a welt gage with which said chisel coacts; mechanism for moving said work support and knife in one direction a predetermined distance and returning them to their normal position; and means for moving the chisel into contact with the edge gage prior to the cutting stroke of the knife and removing it from the work prior to the return stroke of the knife.

90 28. In a machine of the class described, a work supporting block having a vertical groove therein; an operating tool having its body portion mounted in said groove and provided with a bevelled edge; an adjustable pin movable endwise in said block having a bevelled face coacting with said bevelled edge, said pin being of equal diameter its entire length; and means for clamping said pin in adjusted position.

95 29. In a machine of the class described, the combination of a work support; a channeling knife mounted therein; means for re-

ciprocating said work support; a presser foot coacting with said work support; a rod on which said presser foot is mounted; means for adjusting said presser foot endwise relatively to said rod; a housing on the lower end of said rod having a cylindrical opening therethrough; a revoluble eccentric fitted to said opening; and a pivoted bearing surrounding said rod at a point intermediate 10 its ends.

30. In a machine of the class described, the combination of a work support; a channeling knife mounted therein; means for reciprocating said work support; a presser 15 foot; a rod having a transverse slot in its upper end in which the butt end of said presser foot is adjustably mounted; means for retaining said presser foot in adjusted position; and means for simultaneously 20 parting to said rod reciprocatory and oscillating movements.

31. In a machine of the class described,

the combination of a work support on which one face of the work is adapted to rest; a channelling knife mounted therein; means 25 for reciprocating said work support; a presser foot adjacent the opposite face of the work; and an eccentric actuating said presser foot and forcing it toward said work support into contact with the work on said 30 support during the return stroke of the channelling knife, thereby feeding the work into position preparatory to another cutting stroke of said knife.

Signed by us at 746 Old South Building, 35 Boston, Mass., this 5th day of January, 1922.

LAWRENCE E. JOHNSON.

OTTO T. PETERSON.
